UNITED STATES PATENT OFFICE

AXEL FOLKE CARLSON, OF CAMBRIDGE, MASSACHUSETTS, ASSIGNOR TO REECE SHOE MACHINERY COMPANY, OF BOSTON, MASSACHUSETTS, A CORPORATION OF MAINE

PRESS FOR CUTTING OR PUNCHING SHEET MATERIAL

Application filed November 10, 1926. Serial No. 147,470.

This invention relates to presses for cutting or punching sheet material, and the principles are herein shown applied illustratively to a type of press adapted especially for die-cutting out leather or similar material to produce the constituent parts of various articles such as the uppers of boots and shoes.

The invention is particularly adapted for, and herein shown applied to, a press which, like that of Patent No. 1,228,834 of June 5, 1917, embodies a heavy frame carrying a flat-wise bed for supporting the leather and an overhanging presser or head adapted to descend upon a loose die placed selectively upon the material and thus force the die through the material, and the overhanging presser being fitted so that it may be swung laterally into and from position above the die, enabling clear inspection of the work between cutting operations, such machines being generally known in the trade as clicking machines.

A general object of the invention is to improve the efficiency and convenience of operation of presses of the kind referred to. A particular object is to afford a clicking press wherein the lateral swinging of the presser and its downward actuation by power may both be effected in an improved manner from the same control part or handle. A further object is to provide a controlling part or handle positioned upon the swinging presser itself and so connected with the power actuating means or clutch as to preclude unintended repetition of cutting strokes. Other and further objects and advantages of the invention will be explained in the hereinafter following description of an illustrative embodiment of the invention or will be apparent to those skilled in the subject.

To the attainment of the recited objects and advantages, the present invention consists in the novel press and the novel features of operation, combination, arrangement and detail herein illustrated or described.

In the accompanying drawings Fig. 1 may be considered a left elevation of a clicking machine embodying the present invention, the operator being supposed to stand at the right side of the figure for manipulation of

the leather, the die, the presser head and the actuating mechanism.

Fig. 2 is a detail plan view taken partly in section on the line 2—2 of Fig. 1.

Above the four legs 10 is firmly secured the main frame 11 which constitutes a support for the movable elements of the apparatus. Above the forward part of the frame is the bed or cutting block 12 which may consist of pieces of wood suitably clamped and held as disclosed in said prior patent at the top of a solid support 14 which may be vertically adjustable in the frame by a wheel 13 in order to set the bed at the correct height or distance from the presser, with respect to the height of the die to be used.

The swinging presser or head 15 is shown as arranged to overhang the bed, and the presser has a handle 16 at its forward end, this handle being available and convenient for the bodily lateral swinging of the presser to and from its position over the bed, and over the die 17 which is shown resting upon a hide or piece of leather on the bed. The die might in some cases be attached to the presser, but in the usual operation of the clicker the die is placed selectively on the leather and the presser brought to position over the die and then actuated to descend and return, striking a quick abrupt blow which drives the die cleanly through the material.

The up and down movements of the presser head, in any swung position of the head, are preferably effected by an up and down sliding element 18 in the form of an upright ram or plunger, which preferably reciprocates down and up as in said prior patent, but does not partake of the rotary or swinging movements of the presser, although the ram could be arranged to rotate as well as to carry the presser down and up in each operation.

The ram 18 is arranged in the central rear portion of the machine, behind the cutting bed 12, and is shown engaged by the presser through an upper collar or rotary bearing 19 on the presser and surrounding the ram. The presser and the upper bearing 19 are preferably extended downwardly as at 20 and formed into a lower rotary bearing 21 also surrounding the ram. The downward exten-

sion 20, the two bearings 19 and 21, and the presser 15 may constitute a single integral piece of metal or rigidly connected components. The upper end of the ram 18, within 5 the presser head, may be enlarged so as to form a shoulder preventing relative upward movement of the presser, as in said prior patent.

The weight of the presser and connected 10 parts may be supported through a thrust bearing 23 below the rotary bearing 19 and resting upon a collar 24 adjustably clamped to the ram.

The ram is shown mounted for its up and 15 down movements by an upper fixed bearing 27 and a lower fixed bearing 28 constituting rearward extensions of the main frame 11. The ram moves upwardly and downwardly guided by these heavy rigid bearings, while 20 the actuation of the machine is preferably through power mechanism comprising a clutch and having connection to the lower end of the sliding ram to bring about its downward and upward movements.

25 Referring to the power connections these may start with a pulley 30 adapted to receive a constantly running belt and having sufficient weight to constitute also a fly wheel. Normally disconnected from the pulley is the 30 main or actuating shaft 31 arranged preferably in a central position and extending fore-and-aft near the lower part of the press. The arrangement may be substantially as in said prior patent, involving an eccentric 32 on the 35 shaft 31 and connections for the reciprocation of the ram. A downward extension 34 constituting the lower end of the ram may be connected by an eccentric rod or strap 35 with the eccentric 32. In this way a single 40 rotation of the main shaft causes one downward and return movement of the ram and presser. The rear end of the shaft is shown as carrying a collar or enlargement 40 in which certain of the clutch elements are contained, namely a clutch dog arranged to engage clutch notches or shoulders formed within the fly wheel 30, not shown herein, but indicated in said prior patent. The main shaft 31 may also be surrounded by a friction 45 ring or clamp 42 designed to impose continuous friction and resistance so that the shaft will come promptly to stop when unclutched. Extending forwardly from the clutch dog is shown a pin 48 arranged to cooperate with a cam or shoe 49. As shown in Fig. 1, the shoe is in its rearward position and has cammed the pin 48 away from operative position so as to separate the internal 50 clutch dog from the cooperating shoulders.

As explained in the prior patent it is only necessary to swing forwardly the cam shoe 49, thus disengaging the pin 48 and permitting the engagement of the clutch, to be again 55 disengaged at the end of a rotation as soon

as the cam shoe is allowed to return to its normal position shown.

The downwardly hanging cam shoe 49 which controls the operation of the clutch may be adjustably mounted on a swing member or arm 50 fulcrumed at 51 on a special bracket 52 standing rearwardly from the fixed bearing 28. The arm 50 has an upward extension 54 through which the brake cam or shoe may be operated as will be described. A 70 spring 55 is so combined with the described parts as to tend to throw the brake shoe 49 rearwardly into the position indicated, and a stop 56 determines this position.

The control of the operation from a handle at the forward end of the swinging presser may conveniently be effected as follows. The handle 16 is shown as having a sliding stem 58 extending into a boss 59 formed at the upper side of the presser. The handle is formed with a groove 60 which is engaged by a fork 61 formed at the front end of an operating lever 62 which is normally pulled upwardly by a spring 63 and is fulcrumed upon a stud 64 near the rear end of the presser. The rearward extension of the extension of the operating lever carries a trip dog or finger 65 which is adjustable forwardly and rearwardly by a holding device 66 for purposes to be described. The dog 65 is shown engaged in a hook or pawl 67 and operates to lift the pawl when the handle 16 is thrown down. The pawl 67 has a spring 68 pressing it forwardly into engagement with the dog and the pawl is carried at the upper end of a rod 69 running in suitable recesses in the extension portion 20 of the presser; these parts all partaking of the swinging movements of the presser, and being operative in all swung positions thereof.

100 The sliding rod 69 at its lower end carries a head 70 adjustable on the rod and formed with a hook 71 at its lower end, the head being guided in its up and down movements by a guide bracket 72 formed with a vertical slot engaged by a bolt 73 extending forwardly from the head 70. As all of these parts swing with the movements of the presser the hook 71 is arranged to cooperate with the clutch trip arm 54 through an arc shaped extension 75 thereof laid out with the axis of the ram 18 as a center. This arm shaped extension or head of the arm 54 is shown in plan view in Fig. 2 with the hook 71 engaging under the flange thereof. By this arrangement it follows that no matter where the presser may stand the hook 71 will always be in operative relation with the head 75 of the arm 54. By this arrangement the throwing down of the handle 16 will cause the swinging of the arm 54 and the shifting forwardly of the cam shoe 49 so as to permit the clutch to engage and cause a downward and upward movement of the presser.

105 In order to prevent a repetition or second 130

downward and upward movement of the presser there is shown a tripping roller 77 above the pawl or hook 67, the latter being of such shape as to be cammed rearwardly and caused to disengage from the dog or finger 65 during the upward movement of these parts. The dog 65 should be adjusted and timed so that the dog and pawl will disengage immediately after the power clutch has been caused to engage. In this way the operative can not produce another operation of the press without letting up the handle 16 and deliberately throwing it down for a new operation.

The described mechanism therefore constitutes a convenient hand tripping device meeting the objects before stated. In operation, after the die 17 has been located on the work, and the presser swung thereover by means of the handle 16, the handle may be depressed to cause the power actuation of the head. The operating lever 62 swings down and its rear extension swings up so that the dog 65 lifts the pawl 67 and thereby the rod 69, which in turn causes the swinging of the arm 54 and the forward shifting of the clutch shoe 49. This releases and applies the clutch and immediately afterwards causes the pawl 67 to be cammed rearwardly, disconnecting the handle 16 from the clutch mechanism. The main shaft starts its rotation while the rod 69 and connected parts move back to the normal position shown. Therefore at the end of a single rotation the clutch is again applied and the machine stopped with the presser elevated. A new operation can not be effected without letting up the handle 16 for enough to depress the dog 65 to initial position, where it reengages the pawl 67.

There has thus been described a press for cutting or punching sheet material embodying the principles and attaining the objects and advantages of the present invention. Since many matters of operation, combination, arrangement and detail may be variously modified without departing from the principles it is not intended to limit the invention to such matters except so far as specified in the appended claim.

What is claimed is:

In a clicking press, a work support, a presser swingable laterally over the work support, a power clutch, a clutch lever for throwing the clutch into and out of operation and carrying a concentric arc-piece, a connecting rod movable up and down and partaking of the swinging movements of the presser and carrying a contact engaging said arc-piece, whereby the rod may throw the lever in any swung position, a control lever movably mounted with handle at the free end of the presser; said control lever having a latch part, and said rod having a latch part at its top end engaging the first latch part, the second latch part having a cam surface, and a

fixed part cooperating with said cam surface to throw the second latch part and disengage the latch when said rod is moved by the control lever.

In testimony whereof, I have affixed my ⁷⁰ signature hereto.
